US00D900137S

(12) **United States Design Patent** (10) **Patent No.:** **US D900,137 S**
(45) **Date of Patent:** **** Oct. 27, 2020**

(54) **DISPLAY SCREEN OR PORTION THEREOF
WITH GRAPHICAL USER INTERFACE**

(71) Applicant: **Acordo Certo—Reparacao E
Manutencao Automovel, LTA, Cascais
(PT)**

(72) Inventor: **Nuno Filipe Ramos Ribeiro Godinho
Lopes, Cascais (PT)**

(73) Assignee: **Acordo Certo—Reparacao E
Manutencao Automovel, LTA, Cascais
(PT)**

(**) Term: **15 Years**

(21) Appl. No.: **29/659,834**

(22) Filed: **Aug. 13, 2018**

(30) **Foreign Application Priority Data**

Feb. 12, 2018 (PT) 20182000502271

(51) LOC (12) Cl. **14-04**

(52) U.S. Cl.

USPC **D14/486**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface, showing our new design.

The broken lines in the FIGURE show features that form no part of the claimed design.

**1 Claim, 1 Drawing Sheet
(1 of 1 Drawing Sheet(s) Filed in Color)**
